UNITED STATES PATENT OFFICE.

ELLERY I. GARFIELD, OF LEXINGTON, MASSACHUSETTS.

DESIGN FOR A SPOON.

SPECIFICATION forming part of Design No. 20,896, dated June 30, 1891.

Application filed April 9, 1891. Serial No. 388,295. Term of patent 7 years.

To all whom it may concern:

Be it known that I, ELLERY I. GARFIELD, a citizen of the United States, residing at Lexington, in the county of Middlesex and State 5 of Massachusetts, have invented and produced a new and original Design for the Ornamentation of Spoons, Forks, Knives, or Similar Articles of Table-Ware, of which the following is a specification, reference being had to the 10 accompanying drawing, forming part thereof.

The leading feature of my design consists in a spoon-handle having thereon the configuration of a musket, the handle being provided with suitable ornamentation. As herein 15 shown, the handle is formed in the general shape of a musket, the stock thereof forming the outer end of said handle and the barrel of the musket forming the shank, which extends down toward the bowl of the spoon or 20 corresponding part of the fork, knife, or similar article. Upon the handle or stock of the musket I have shown in the drawing the figure of a minute-man.

In the accompanying drawing, A represents the spoon; B, the handle, having the 25 stock of the musket corresponding with the extended part and the barrel of the musket extending down toward the bowl.

I have shown on the handle of the spoon the word "Concord" and figures "1775;" but 30 it will be obvious that these constitute no part of my invention and may be omitted without departure from the essential feature of my design.

I claim as my invention—

A design for spoons, &c., having the shape and ornamentation substantially as herein shown and described.

In testimony whereof I have hereto set my hand.

ELLERY I. GARFIELD. 35
